UNITED STATES PATENT OFFICE.

CHARLES P. CRAWFORD, OF SALT LAKE CITY, UTAH.

APPARATUS FOR BURNING PULVERIZED FUEL.

Application filed August 25, 1919. Serial No. 319,531.

To all whom it may concern:

Be it known that I, CHARLES P. CRAWFORD, a citizen of the United States, residing at Salt Lake City, in the county of Salt Lake 5 and State of Utah, have invented certain new and useful Improvements in Apparatus for Burning Pulverized Fuel, of which the following is a specification.

This invention has reference to means for 10 the utilization of finely comminuted fuel as a heating agent whereby, among other advantages, the necessity of the preheating of the fuel, and the necessity of using an excessively large volume of air of combustion, or of equivalent means, are dispensed with. It is one of the objects of my invention to 15 utilize the well-known gas-condensing and absorbing, and to some extent catalytic action of finely divided combustible matter, such as coal dust for instance which, when moist is liable to spontaneous combustion, as a means of generating a high degree of heat without the inconvenience resulting from preheating thereof, and from the use 20 of high-power blasts for blowing the material into a large space and mixing it with a large volume of oxygen or air of combustion.

Another object of my invention is to 30 provide efficient means of greatly increasing the heat output of even inferior grades of comminutable fuel, and incidentally to increase the efficiency of closed or open containers heated by such fuel, and to minimize and eliminate the dangers otherwise 35 connected with the use of such fuel.

Other objects and advantages of my invention will appear from the following detailed description thereof, and from its 40 illustration in the accompanying drawing.

In the accompanying drawing I have represented a preferred form of carrying my invention into effect as applied to an ordinary boiler provided with a heating furnace, 45 the parts being shown partly in elevation and partly in section, but it is understood that my invention is not limited to the particular casual practical application shown in the drawing, but in its broader aspects 50 comprises the various means and instrumentalities set forth in the claims.

In the drawing: 1 shows a conventional form of boiler; 2 is the brickwork of the furnace masonry provided with the customary fire doors, and ash doors conventionally indicated on the drawing; 3 is the

baffle or fire bridge wall from which a flue surrounding part of the boiler extends to the rear thereof; 4 is a water leg, provided with a longer leg 5, and a shorter leg 6, 60 which latter is preferably arranged near the front part of the boiler; 7 is a chute or feeding tube connected to the coal supply, not shown in the drawing, and leading into the hopper 8. 15 is a mixing tube or the like, 65 projecting through the brickwork 2 into the interior of the furnace, any suitable part of which is mounted within the interior of the water leg 4. 16 is a nozzle at the free end of the tube or chamber 15, projecting 70 through the wall of the tube or water leg 4, and preferably directed toward the front part of the boiler.

The tube or chamber 15 communicates with the bottom part of the hopper 8, a 75 feed screw 9, or similar means being arranged within the hopper at or near its junction with the chamber or tube 15. 10 is the driving shaft for the feed screw 9, the shaft being connected to a source of motion by 80 means, not shown in the drawing. 13 is a steam connecting pipe establishing communication from the boiler with the chamber or tube 15, preferably in front of the fuel delivery means; 11 indicates diagrammatically a steam injector, controlled by valve mechanism 14, of which 12 is the shut-off and steam-admitting valve or the like.

The herein-described instrumentalities operate as follows:—The finely disintegrated 90 fuel, coal-dust for instance, is intimately mixed with steam in the mixing chamber 15, which is protected against radiation of heat by its being surrounded by the water leg 4. Owing to the condensing and catalytic action 95 of the coal dust a large amount of the steam is dissociated very much below the dissociation temperature of water, carbon monoxid and hydrogen being some of the products of the reaction with coal dust similar 100 to the formation of water gas. A strong draft being created at the discharge nozzle or nozzles 16 by outside air, not shown in the drawing, or otherwise, the gaseous highly combustible products of the reaction are immediately carried off, the combustible mixture escaping from the nozzle or nozzles being partly gaseous so that a substantially complete smokeless combustion is obtained, the device acting as a continuous gas producer, effecting the combustion by means of 110 hydrocarbons and water vapor, a complete

2
combustion being thus obtained almost instantaneously.

The steam is employed either as saturated or superheated steam. The reaction is assisted by the provision of the water leg 4, which receives the heat directly from the gases ascending from the nozzle or nozzles 16, or reflected from the walls of the furnace, and the upwardly and forwardly inclined arrangement of the water leg 4, is particularly advantageous because by this means a long flame is produced, and the flame with the assistance of outside air admitted through a grate or the like, as above described, flows substantially parallel with the slope of the water leg 4, and is uniformly in contact for its entire length with said water leg. The water leg also causes the boiler water to circulate freely, which is very desirable. At the same time a temperature is maintained in the mixing chamber 15, substantially equal to the temperature of the steam when it strikes the pulverized coal, and the flame in the form of construction shown in the drawing is projected towards the fire door and away from the flues. The type here shown as an instance of carrying my invention into effect, will be desirable for locomotive burners.

My invention may be employed in combination with various forms of heating and burning devices, and it may be applied to all kinds of open or closed containers in which the temperature of the contents thereof are raised, and the vapor or steam upon the mutual reaction of which the finely disintegrated fuel my invention depends may be generated in any suitable manner. Various other modifications and means of application and utilization of my invention will suggest itself to the expert in accordance with the necessities of local conditions, my invention not being confined to any particular forms of realization thereof except as appears from the claims hereunto appended.

While I have shown my invention as sup-

plied with one chamber 15 and one by-pass 4, it is obvious that a plurality of such by-passes, and a plurality of mixing chambers 15 having nozzles 16, may be used. In such case the arrangement may be similar to that of the superheater tubes in locomotive boilers. Also the inclination of the by-pass 4 may be changed, the by-pass being, for instance, parallel to the boiler. 55

What I claim is:

1. In a heating and burning device, the combination with a boiler and a furnace chamber surrounding part of said boiler, of forwardly inclined tubular liquid circulating means at the outside of the boiler and communicating therewith within said chamber, fuel delivery means leading from the outside into the interior of said liquid circulating means and projecting therethrough into said chamber, fuel supplying means at the outer end of said delivery means and communicating therewith, and means for leading vapor from the boiler to said delivery means adjacent said fuel supplying means. 60

2. An apparatus for burning pulverized fuel, consisting of a furnace, a boiler above said furnace, a water leg depending from the boiler into said furnace, a fuel feeding pipe 75 extending from the outside of the furnace into said water leg and coaxially therewith for a portion of its length, and through the wall thereof into the furnace, a discharge nozzle secured to the inner end of said pipe, a fuel supply hopper communicating with said pipe, a feed chute leading to said hopper, a feed screw in said hopper, and steam injecting means leading from the boiler to the fuel feeding pipe. 80

In testimony whereof I affix my signature in the presence of two witnesses.

CHARLES P. CRAWFORD.
